A. A. SMITH

ATOMIZER

Filed July 22, 1921

Inventor
Albert Abuzo Smith
By his Attorney
Abel L. Brownrigg

UNITED STATES PATENT OFFICE.

ALBERT ALONZO SMITH, OF NEW HAVEN, CONNECTICUT, ASSIGNOR TO JOHN ADAMS
MOFFITT, OF BRONXVILLE, NEW YORK.

ATOMIZER.

Application filed July 22, 1921. Serial No. 486,801.

To all whom it may concern:

Be it known that I, ALBERT ALONZO SMITH, a citizen of the United States, and resident of New Haven, in the county of New Haven and State of Connecticut, have invented certain new and useful Improvements in Atomizers, of which the following is a specification.

This invention relates generally to atomizers and particularly to an atomizer having a spray distributing nozzle mounted to be rotated in its seat about its main longitudinal axis.

It is an object of this invention to provide an improved atomizer of the general type referred to in which special means are provided for preventing leakage at the point of juncture of the rotatably mounted nozzle with the reservoir closure or cap. Another object of the invention is to provide an atomizer in which the two-fold action of both pressure and suction are utilized in discharging liquid from the container in order to produce a doubly effective continuous spraying action. Other features of the invention will be hereinafter referred to.

In the single view comprising the drawing, a preferred form of the invention is shown partly in section and partly in side elevation.

Referring to the drawing, a container or reservoir 1 for the spray liquid is provided with a screw top 2 adapted to be attached to the container and form an air-tight joint therewith. A curved spray nozzle 3 is mounted at one end in the side of the screw top 2 and may be rotated in its seat to cause the discharge end 4 thereof to be presented at an angle to the axis of rotation and in any desired lateral direction.

The cap member 2 is provided with an internally threaded bore 5 adapted to engage the correspondingly externally threaded neck 6 of the container 1, and with a flange or skirt member 7 which has supporting engagement with a shoulder 8 on the container. A suitable washer 9 is ordinarily provided to form an air-tight joint between the container 1 and the container closure member 2.

The cap member 2 is provided with an air inlet passage 10 terminating at one end in a flanged nipple 11 on one side of the cap member, the nipple 11 being formed to receive the end of a section of flexible rubber tubing leading from a rubber bulb or other

air compressor. The other end of the angular or L-shaped passage 10 terminates within the bore 5 in communication with the interior of the container 1, as will be seen.

The container top 2 is provided also with two outlet or discharge passages leading from the interior of the container, one of these passages 12 communicating with a downwardly projecting tube 13 which projects into the spray liquid 14 in the container. The other end of the passage 12 flares outwardly into an opening 15, provided in the side of the cap 2 substantially opposite the nipple 11. The other discharge passage 16 in the container top 2 affords a means of communication between the opening 15 in the top 2 and the interior of the container 1.

Communication between the discharge passages 16 and 12 referred to and the spray tube nozzle 3 is brought about in the following manner. The spray tube 3 is of a compound construction and consists of the outer tube 4' and an inner tube 17. The inner end of the inner tube 17 has a tapered formation fitting the correspondingly flared end of the passage 12, while the outer tube 4' has a tapered construction to fit a conical seat 18 with which the opening 15 in the container top 2 is provided. It will thus be seen that the passage 12 and liquid receiving tube 13 communicate directly with the inner tube 17, while the outer tube 4' communicates through the port or passage 16 with the air space within the container 1.

In order to hold the flaring ends of the tubes 4' and 17 to their seats a threaded nipple 19 is formed on the side of the top 2 the bore of which is concentric with the opening 15. An internally threaded collar 20 is formed to engage a flange 21 formed on the tube 4' and to engage the threaded nipple 19. The collar 20 forms a gland or stuffing box which can be supplied with a washer 22 or other packing material to form a tight joint and at the same time permit the tubes 4' and 17 to rotate on their concentrically formed seats.

In operation pressure produced in the container 1 above the liquid through the introduction of air through the passage 10 causes liquid to rise in the tube 13 and to flow into the inner spray nozzle tube 17 and to be discharged from the small port 23 in the outer end thereof into engagement with the discharge port 24 in the cap 4 from which the

liquid issues in the form of a spray. At the same time air pressure in the container 1 passes through the passage 16 into the outer spray nozzle tube 4', an air stream being thus caused to produce an aspirating effect on the contents of the inner tube 17 as the stream flows past the port-containing terminal of the inner tube. It will thus be seen that both pressure and suction are exerted on the contents of the inner tube, pressure by way of the tube 13 and suction produced at the discharge extremity of the tube through the aspirating action of the air discharged from the outer tube.

It will also be seen that the curved formation of the spray nozzle and the rotatable mounting of the nozzle in its seat provides for directing the tip or discharge end of the nozzle in an upward, downward or other direction bearing an angular relation to the axis of rotation of the nozzle as desired, the air and liquid-tight joint provided by the collar 20 preventing leakage of spray fluid while permitting the desired rotation of the spray nozzle. While the nozzle has been described and shown as having a curved formation, it will be clear that a straight line or other formation can also be employed, providing that the discharge end of the nozzle can be directed at an angle to the main axis thereof.

What I claim is:

1. In an atomizer, a container, a closure top for said container, a passage in said closure top through which air pressure may be forced into said container, a tube supported by said top and extending downwardly into the space for liquid in said container, a spray nozzle mounted on said closure top and communicating with said downwardly extending tube, said spray nozzle being curved laterally with relation to its longitudinal axis with the tip of the nozzle positioned in a prolongation of the axial line passing through the base of the nozzle and mounted to rotate in its seat in said closure top whereby to change the direction of projection of the spray, and said spray nozzle being provided with a flange and means engageable with said flange and said closure top for holding said spray nozzle in its seat.

2. In an atomizer, a container, a closure top for said container, a passage in said closure top through which air pressure may be forced into said container, a tube supported by said top and extending downwardly into the space for liquid in said container, a spray tube mounted on said closure top and communicating with said downwardly extending tube, said spray tube being rotatable in its seat and having a curved formation with the tip portion positioned in the axis of rotation of the tube, and a

second tube mounted in surrounding relation to said first tube, said second tube being rotatable in its seat and communicating with the interior of said container whereby air pressure discharged therefrom at the discharge end of said spray tube aids in the discharge of spray therefrom.

3. In an atomizer, a container, a closure top for said container, a passage in said closure top through which air pressure may be forced into said container, a tube supported by said top and extending downwardly into the space for liquid in said container, a curved spray tube mounted on said closure top and communicating with said downwardly extending tube, said tube having a tapering end and said closure top being provided with a conical seat to receive said tapered end, and a second curved tube mounted in surrounding relation to said first-named tube and having a tapered end, the discharge tips of said curved tubes being located in the axial line of the tapering ends, said closure top having a conical seat for the tapered end of said second tube, said conical seats being separated longitudinally of the axis of said tubes, said first-named conical seat being in communication with said downwardly extending tube whereby to connect said spray tube with said downwardly extending tube, and said closure top being provided with a passage for placing the second-named conical seat in communication with the interior of said container whereby air pressure may flow through said second-named tube in aspirating relation to the discharge end of said spray tube.

4. In an atomizer, a container, a closure top for said container, a passage in said closure top through which air pressure may be forced into said container, a tube supported by said top and extending downwardly into the space for liquid in said container, a spray tube mounted on said closure top and communicating with said downwardly extending tube, a second tube mounted on said closure top and communicating with the interior of said container, said second tube being provided with a circumferential flange, said closure top being provided with a threaded nipple surrounding the point of connection of said tubes with said closure top and a threaded collar mounted in surrounding relation to said second tube and arranged to engage said circumferential flange and said threaded nipple to thereby hold said tubes in place and permit the rotation of said tubes in their seats, said tubes being curved laterally with relation to their longitudinal axes but having their discharge tips located in the axis of rotation.

ALBERT ALONZO SMITH.
